BARRICADE

Ewing D. Nunn, Jr., 2430 Terrazo Place,
Fullerton, Calif. 92632

Filed June 6, 1966, Ser. No. 2,569

Term of patent 7 years

(Cl. D72—1)

Fig. 1.

FIGURE 1 is a perspective view of a barricade embodying my new design; and

FIGURE 2 is a front elevational view thereof, the rear being a mirror image of the front shown.

The dominant features of my design reside in the portions shown in full lines, the design being characterized by the elongated box-like unit having a panel supported from its underside in conjunction with the support rod and legs of the barricade as shown.

I claim:

The ornamental design for a barricade, as shown and described.
